CLAIM

The ornamental design for a lawn mower, as shown and described.

DESCRIPTION

1. Lawn mower
- 1.1 : Front
- 1.2 : Back
- 1.3 : Left
- 1.4 : Right
- 1.5 : Top
- 1.6 : Bottom
- 1.7 : Perspective

The present designs show a lawn mower; reproductions **1.1** is a front view of the lawn mower showing the new design; **1.2** is a back view thereof; **1.3** is a left view thereof; **1.4** is a right view thereof; **1.5** is a top view thereof; **1.6** is a bottom view thereof; and **1.7** is a perspective view thereof; the lighter contrast of the lawn mower in the reproductions is shown to illustrate environment and forms no part of the claimed design.

1 Claim, 7 Drawing Sheets
